UNITED STATES PATENT OFFICE.

JOHN BATH, OF WORCESTER, MASSACHUSETTS, ASSIGNOR TO JOHN BATH & COMPANY, OF WORCESTER, MASSACHUSETTS, A CORPORATION OF MASSACHUSETTS.

ADJUSTABLE PLUG GAUGE.

Application filed June 3, 1920. Serial No. 386,258.

To all whom it may concern:

Be it known that I, JOHN BATH, a citizen of the United States, residing at Worcester, in the county of Worcester and State of Massachusetts, have invented a new and useful Adjustable Plug Gauge, of which the following is a specification.

This invention relates to an adjustable plug gauge, particularly adapted for sizing holes in rotating work. It is customary to use a solid steel gauge for such operations, all parts of which are of fixed diameter. Sometimes these gauges are made of two diameters representing the over and under limits of size, which gauges are commonly called "go and no-go" gauges.

It is the general object of my invention to provide an improved gauge of the latter type, which shall not only have portions representing the fixed over and under limits, but also an interposed adjustable portion by which any desired diameter between the limits may be indicated.

My invention further relates to arrangements and combinations of parts which will be hereinafter described and more particularly pointed out in the appended claims.

A preferred form of my invention is shown in the drawings, in which—

Fig. 1 is a side view of my improved gauge;

Fig. 2 is a horizontal sectional view of the gauge shown in Fig. 1;

Fig. 3 is an end view looking in the direction of the arrow 3 in Fig. 2; and

Fig. 4 is a transverse sectional elevation taken along the line 4—4 in Fig. 2.

Referring to the drawings, my improved gauge comprises a shaft 10 having a threaded portion 11, a cylindrical portion 12, a conical portion 13, and an outer threaded end portion 14. A handle 15 is secured to the shaft 10 by a taper pin 16, or in any other convenient manner. A head 17, having a general cylindrical shape, is firmly seated on the conical portion 13 of the shaft 10, being secured thereon by a key 18, and a binding nut 19.

The head 17 is provided with a plurality of inclined dove-tailed guide-ways 20 in which tapered gauge bars 21 of dove-tailed cross section are slidably mounted. A flanged sleeve 22 is slidable on the cylindrical portion 12 of the shaft 10, and may

be adjusted thereon by a collar 23 threaded 55 on the portion 11 of the shaft 10. The collar is preferably provided with a series of holes 24, to which a spanner wrench may be applied.

A flanged member 25 is threaded on the portion 14 of the shaft 10, and is provided with a cylindrical extension 26 fitting a recess 27 in the end of the head 17. A binder nut 28 holds the member 25 firmly in adjusted position. The member 25 is provided with a series of holes 29 also adapted to receive a spanner wrench.

The external surfaces of the sleeve 22 and the member 25 constitute gauging surfaces of determined size, the member 25 being 70 commonly a few thousandths of an inch smaller in diameter than the member 22.

Having described the construction of my improved gauge, I will now set forth the advantages and use thereof.

The gauge bars 21 may be adjusted relatively to the head 17 by loosening the lock nut 28 and by moving the collar 23 and the member 25 in one direction or the other to slide the gauge bars relative to the head 17. 80 By such movement the gauge bars may be brought to the exact required diameter, in which position they are retained by the lock nut 28. This exact diameter may be determined by reference to any suitable measuring device such as an outside micrometer caliper or a standard ring gauge.

When the gauge is used for measuring rotating work, the member 25 is commonly made of a size just under the required size 90 of the hole, the gauge bars 21 are set to have a close running fit in a hole of the required size, and the flanged collar 22 is of such external diameter that it will not enter the hole unless the hole is oversize.

The work is first ground out more or less rapidly until the member 25 will enter the hole. The hole is then enlarged very slowly until the gauge bars themselves will enter the hole with a close running fit. When the gauge bars will thus enter the hole but the flanged sleeve 22 will not enter the hole, the hole is known to be of the exact desired size. If the flange 22 does enter the hole, the hole is oversize, and the work must be discarded.

When used with rotating work, the parts are of course subject to rather rapid wear,

which may, however, be easily taken care of by supplying a new flanged member 25 and by adjusting the bars 21 as often as may be necessary. The wear on the flanged sleeve 22 is or should be very slight. The parts 21, 22 and 25 are made to interchangeable standards and these parts may any of them be readily replaced if worn.

5 The handle or sleeve 15 may be removed 10 from the shaft 10 by driving out the pin 16. Such removal permits the sleeve 22 to be removed and replaced if desired. The hole 30 in the handle 15 is of advantage in preventing rotation of the handle when loosening 15 the lock nut 28 or the member 25.

Having thus described my invention it will be evident that changes and modifications can be made therein by those skilled in the art, within the spirit and scope of my 20 invention as set forth in the claims, and I do not wish to be otherwise limited to the details herein disclosed, but what I claim is:—

25 1. An adjustable plug gauge, having, in combination, a support, separated gauge members mounted thereon and of different fixed sizes, a plurality of gauge bars adjustably mounted on said support between said members and closely adjacent thereto, and means to adjust said bars radially to sizes intermediate said fixed sizes.

30 2. An adjustable plug gauge, having, in combination, a shaft, a pair of gauge members of different fixed sizes held in separated positions on said shaft, a plurality of gauge 35 bars positioned between said gauge members, and means to adjust said bars simultaneously radially of the axis of said shaft.

35 3. An adjustable plug gauge, having, in combination, a shaft, a head fixed to said shaft and having dove-tailed grooves therein inclined toward the axis of said shaft, a plurality of dove-tailed gauge bars relatively 40 slidable in said grooves, a pair of gauge members on said shaft, engaging the ends of said bars to longitudinally position said bars relative to said head, and means to change the axial position of said members relative 45 to said shaft and head, thereby adjusting said bars in said head.

40 4. An adjustable plug gauge having, in combination, a shaft, a gauge member mounted on said shaft and of a determined size, a second gauge member mounted on the end of said shaft and of a determined but 45 smaller size, a plurality of adjustable gauge bars positioned between said members, and

means to adjust said bars radially to sizes between the sizes of said two members.

5. An adjustable plug gauge comprising a shaft, having, intermediate and end 60 threaded portions, a plurality of gauge bars, a head fixed to said shaft and having tapered guide-ways for said gauge bars, said head having a cylindrical recess therein, a member threaded on said shaft and having a projection fitting said recess, a lock nut for said member, a sleeve slidable on said intermediate portion, said member and said sleeve positioning said bars longitudinally relatively to said shaft, and a collar threaded on said 65 intermediate portion and effective to move said sleeve axially.

6. An adjustable plug gauge, having in combination, a shaft having separated threaded portions including an end portion 70 and having also an interposed cylindrical portion, a head fixed to said shaft adjacent said cylindrical portion, a plurality of gauge bars supported by said head, and means to adjust said bars axially on said head, said 75 means including a flanged sleeve fitting said cylindrical portion of said shaft and having an external gauging surface, an adjusting collar therefor threaded to said shaft, and a flanged member mounted on the threaded 80 end portion of said shaft and having a bearing in said head, said member also having an external gauging surface of relatively 85 smaller diameter.

7. An adjustable plug gauge having, in 90 combination, a plurality of gauging members, a shaft having an intermediate threaded portion, means fixed on said shaft for supporting said gauging members thereon, and means to adjust said members, said 95 latter means including a collar threaded on said intermediate portion of said shaft, and a handle sleeve removably fixed to said shaft and normally preventing removal of said collar from said shaft.

8. In an adjustable gauge, a supporting shaft having a conical intermediate portion, a head seated on said conical portion, means to hold said head from angular or axial movement on said shaft, a plurality of gauge 105 bars slidably mounted in said head, and means to move said bars axially relatively to said shaft.

In testimony whereof I have hereunto affixed my signature.

JOHN BATH.
